COAL HEAVER

Harry C. Hill, Pittsburgh, Pa.

Application September 8, 1949, Serial No. 114,655

4 Claims. (Cl. 198—7)

1

My invention consists in a new and improved mechanism or coal heaver for conveniently conveying solid fuel preferably in the form of small lumps from a supply source, such as a cellar bin, to the hopper of a mechanical stoker.

In the case of mechanical stokers, especially those in domestic use, the stored supply of fuel is usually located at some distance from the stoker, thus preventing the replenishment of the latter with fuel except by considerable effort, such as by carrying the fuel for some distance in a shovel, such distance being too great to permit the attendant to reach the hopper of the stoker by a single swing of the shovel without spilling a portion of the shovel load.

Thus the job of providing an adequate supply of fuel to the hopper is laborious and time-consuming, and usually involves the soiling of clothing and the distribution of dust in the atmosphere.

The object which I have in view is the provision of a small portable implement which may be pushed by the operator along the floor of a storage bin or into a mass of fuel to automatically pick up the latter and move it into the intake of a flexible conduit in which is mounted a screw conveyor, power-driven as by an electric motor mounted on the implement, which conveyor causes the picked up fuel to travel lengthwise through the flexible conduit to the discharge end of the latter which preferably is inserted into the top of the stoker hopper.

Other novel features of construction and arrangement of parts appear in the following description.

In the accompanying drawings, in which I illustrate my preferred embodiment of the principles of my present invention,

Fig. 1 is an end elevation of the implement, looking from the left in Fig. 2;

Fig. 2 is a front elevation of the implement;

Fig. 3 is a broken longitudinal section of the flexible conduit, showing the screw conveyor extending within the same, and

Fig. 4 is a cross-sectional view, on enlarged scale, taken along the line 4—4 in Fig. 3.

Referring to the drawings, the outer housing or casing of the implement is formed of metal of proper thickness to provide the required strength and rigidity, and which is shown as comprising the horizontal flat floor 10 which extends forward materially beyond the front of the top wall 11 and the opposite end walls 12. 13 indicates the rear wall of the casing which extends up vertically from the rear edge of the floor 10. The top enclosure or wall 11 of the casing merges at its rear edge with the top of the rear wall 13. The top wall 11 extends upwardly and forwardly from the rear wall 13 in dome form to provide a space in which is mounted an electric motor 15 positioned at an elevation above the floor 10, as upon the platform 16.

2

The top wall 11 extends downwardly and outwardly as shown in Fig. 1 and also its end edges diverge outwardly to extend to the planes of the side edges of the floor 10.

5 The front edge of the top wall 11 is spaced above the floor 10, thus providing a gateway 17 in the form of an elongated rectangular slot extending for the full width of the floor 10 and stepped back from the front edge 18 of the latter, which edge extends forwardly to act as a scoop which picks up the fuel, as the implement is shoved forward, and feeds the same to the screw conveyor through the gateway 17.

15 indicates a section of the screw conveyor mounted in the casing just within the gateway 17 and extending for the full length of the same. The discharge end of the section 19, the right end in Fig. 2, has its axial shaft 20 provided with a spaced concentric ring 21 supported from the

20 shaft 20 by the radially extending rib or ribs 22, and the ring 21 is journaled in the collar 23 which, in turn, is rigidly mounted in an opening in the adjacent end wall 12 of the casing. The other end, the left end of the conveyor section 19 extends through a bearing in the opposite end wall of the casing and has mounted thereon a screw worm gear wheel 24 which is in mesh with the horizontal worm shaft 25 journaled in a boxing 26 which also encloses the gear wheel 24.

30 The rear end of the worm shaft 25 is provided with a pulley 27 which is connected by the belt 28 with a pulley 29 mounted on the front end of the power shaft of the motor and which extends through a bearing in the wall of the housing. A boxing 30 is provided for the pulleys 27 and 29 and the belt 28 to protect them from dust. Both the boxings 26 and 30 are detachably attached to the main housing of the implement and are thus readily removable for cleaning or repair

35 of the mechanism enclosed therein. Energy is supplied to the motor by means of the extension conductor 31 which leads up through the hollow operating handle 32, past the switch 33 to a plug for connecting the conductor to the house wiring. 40 The collar 23 protrudes outwardly through the wall of the casing as shown in Fig. 2 so that the intake end of the flexible cylindrical conveyor conduit 34 may be stepped in the collar to attach the conveyor in operative position. Suitable means, not shown, may be employed to hold the conduit fast to the ring.

45 The screw conveyor within the conduit 34 is formed in relatively short sections, the axial shafts 35 of which are connected together at their adjoining ends by the universal joints 36 and the shaft of the first shaft section at the receiving end of the conduit is likewise joined to the shaft 20 of the screw conveyor mounted in the gateway.

50 Thus the conduit which may be formed of rubber, spirally wound metal strips, or of other suitable materials, remains flexible and may be

directed into the proper position to deliver fuel to the stoker hopper or other depository and will accommodate itself to changes in position as the implement is moved along to pick up fuel and feed it to the conduit.

There are two very important advantages gained by the use of my improved coal heaver.

Thus in a domestic establishment wherein women or elderly persons are charged with maintaining a continuous supply of fuel to a mechanical stoker, the use of a shovel or basket for conveying the fuel from a bin to the hopper of the stoker is a burden too great, but which my improved implement effects mechanically except for the slight physical effort required of pushing the implement along the floor of the bin to feed the fuel into the gateway, which is easily accomplished.

Again, where a foreign substance, such as a nail, bolt, nut, a piece of wire, a stone or piece of wood gets into the hopper of a stoker and is picked up by the feeding mechanism of the device, the screw feeder admitting the fuel to the firebox becomes jammed and breaks the shear pin, provided for that purpose, and it is necessary to remove the exterior end wall of the screw feeder container, back out the obstruction, put in a new shear pin, and reassemble the mechanism. Consequently the stoker may be out of service for several hours or days, depending upon the time required to obtain the services of a repair workman. Any object which will pass through the coal heaver will also pass through the stoker.

In the case of my improved coal heaver when such a foreign object is picked up by the heaver it stops the pick-up conveyor by throwing off the drive belt. Then the pick-up conveyor may be reversed in motion, as by means of a wrench and the foreign object backed out. The belt may then be replaced and the heaver is ready for operation. Such a repair does not require the services of a skilled mechanic.

I claim:

1. An implement, for conveniently conveying solid fuel from a relatively remote fuel bin or other supply to the intake of a mechanical stoker, which consists of a housing containing an electric motor, flexible means for supplying operating current to the motor, the front of the housing being provided with a horizontally elongated gateway with the floor of the housing extending forwardly therefrom to form a scoop for the intake of fuel as the housing is shoved forwardly into the supply of fuel, a screw conveyor section driven by the motor and mounted in the housing in the rear of and parallel with the gateway and arranged to receive the fuel scooped into the housing, means defining a port in the wall of the housing at the delivery end of said conveyor section through which the fuel is discharged by said conveyor, a flexible conveyor tube having its intake end connected to said port arranged to receive fuel from the discharge end of the screw conveyor section, and means operatively connected to said screw conveyor and operated thereby extending longitudinally of the tube for causing the fuel to travel through the tube to the opposite extremity of the latter.

2. An implement, for the purposes described, comprising a housing provided with a horizontally elongated gateway in its front wall and a floor extending forwardly of the gateway to form a scoop to feed fuel inwardly through the gate-

way as the implement is pushed forwardly into a mass of fuel, a screw conveyor section mounted to rotate in the housing in the rear of the gateway to receive fuel therethrough, means forming a port in the side wall of the housing at the delivery end of the screw conveyor section, a flexible conveyor tube having its intake end connected to said port and to which the fuel is fed by said conveyor section, flexible screw conveyor sections mounted within said tube arranged to cause the fuel received from the first mentioned conveyor section to travel through the tube to the delivery end thereof, and means mounted within the housing to rotate all of said conveyor means in unison.

3. An implement, for the purposes described, comprising a housing provided with a horizontally elongated gateway in its front wall and a floor extending forwardly beyond the gateway to form a scoop to admit fuel to the housing as the implement is pushed forwardly into a mass of solid fuel, a screw conveyor section rotatably mounted in the housing in the rear of said gateway and to which the fuel is fed by the advance of the implement, a port in one end wall of the housing through which the fuel is fed by the rotation of the conveyor section, a flexible tube having its intake end connected to said port to receive fuel fed by the conveyor section, and a plurality of aligned screw conveyor sections in said housing and operatively connected to the first mentioned conveyor section to rotate in unison therewith and cause the fuel to travel along the flexible tube to the delivery end thereof.

4. An implement, for the purposes described, comprising a housing provided with a horizontally disposed opening in its front wall to form a gateway and the floor of the housing extending forwardly of the gateway to provide scoop means to feed fuel inwardly of the housing as the implement is moved forwardly into a pile of fuel, an electric motor mounted within the housing, a conveyor screw driven by said motor and mounted to rotate in the housing in the rear and parallel to the gateway to engage the fuel introduced through the latter, means forming a port in the side wall of the housing at the delivery end of the screw conveyor, a flexible conveyor tube having its inner end connected to and communicating with the port, and a flexible screw conveyor structure extending longitudinally within the tube and operatively connected to the first mentioned screw conveyor to rotate therewith to cause the fuel delivered by the conveyor screw to the tube to travel out through the length of the latter.
